FAUCET ASSEMBLY

Paul R. Maguire, Los Angeles, Calif., assignor to Adams Rite Manufacturing Company, Glendale, Calif., a corporation of California

Filed Aug. 29, 1966, Ser. No. 3,631

Term of patent 14 years

(Cl. D91—3)

FIG. 1.

FIG. 2.

FIG. 3.

FIG. 4.

FIG. 5.

FIG. 1 is a perspective view of a faucet assembly showing my new design;

FIG. 2 is a top view of the same;

FIG. 3 is a front elevational view thereof;

FIG. 4 is a rear elevational view thereof; and

FIG. 5 is an elevational view taken from one side thereof.

The dominant features of my design reside in the portions shown in full lines, it being understood that the fragmentary broken line showing of a sink in FIGS. 1 and 2 is for purposes of illustration only.

I claim:

The ornamental design for a faucet assembly, substantially as shown and described.
